UNITED STATES PATENT OFFICE.

WILLIAM H. THURMOND, OF FORSYTH, GEORGIA.

BOILER WASHING-MACHINE.

SPECIFICATION forming part of Letters Patent No. 295,462, dated March 18, 1884.

Application filed June 14, 1883. (Model.)

To all whom it may concern:

Be it known that I, WILLIAM H. THURMOND, a citizen of the United States of America, residing at Forsyth, in the county of Monroe and State of Georgia, have invented certain new and useful Improvements in Boiler Washing-Machines, of which the following is a specification, reference being had therein to the accompanying drawings.

10 My invention relates to wash-boiler fountains; and it consists in the novel construction of its parts, as particularly described and claimed in this specification, and fully illustrated in the accompanying drawings, to which reference is made.

In the drawings, Figure 1 is a vertical section of my fountain, and Fig. 2 is a plan view of the bottom of the same.

Like letters of reference indicate corresponding parts in the views.

The letter A is a wash-boiler fountain made of glass. Short supports or legs are formed on its bottom. It has two or more openings, D D, through its bottom, for the entrance of steam and water into the chamber or cavity A'.

G is a solid rounded elevation of the bottom of the fountain for reducing the capacity of the cavity A', and for adding weight to the fountain.

30 A tube, B, of tin or malleable metal, is inverted in an opening in the top of the fountain A, which communicates with the cavity A'.

Over this tube B another tube, C, is placed, snugly fitting the former, and adapted to be raised or lowered, as desired. The tube C is provided with a cap, or has its upper part spread at a slight angle, which cap or upper part is laterally perforated with three or more holes for the exit of the steam and water forced up from the cavity A'. The top of the tube C is of course closed.

Instead of the shape of the bottom of my fountain shown in solid lines, I also form it as indicated by the dotted lines xx , the letters x' denoting two or more openings for the entrance of the water.

The following dimensions I have found to give the best results for washing clothes in an ordinary wash-boiler. The diameter of the body of the machine is eight(8) inches, height of body about five (5) inches, with the inner cavity, A', about two by five inches. The holes D D are about one and one-fourth inch in diameter. The tubes B and C are one and three-fourths inch in diameter and about twelve inches long and the holes c c near the top should correspond in number and size with those in the bottom of the fountain.

By making the body of my fountain of glass it will absorb heat and rapidly rarefy the water and steam entering the chamber A', which will therefore ascend the tube B and pour out upon the clothes in the boiler. The current thus produced, forcing the heated soapy water through the clothes, rapidly cleanses them without the harsh treatment of rubbing or pounding.

I am aware that it is not new in wash-boilers to employ a hollow ring having a tube rising from one side of it, and therefore I make no claim to such a device.

Having thus described my invention, what I claim as new, and desire to secure by Letters Patent, is—

The within-described new article of manufacture, the same consisting of the hollow body A, having supports a , perforations through its bottom, and a central elevation, G, in combination with the centrally-arranged fixed tube B and the adjustable tube C, having a closed top and perforations through its sides, substantially in the manner and for the purpose described.

In testimony whereof I affix my signature, in presence of two witnesses, this 20th day of February, 1883.

WILLIAM H. THURMOND.
